UNITED STATES PATENT OFFICE.

DAVID D. MORRIS, OF PATERSON, NEW JERSEY.

VALVE-GUARD.

1,832,513.

Specification of Letters Patent.

Patented Mar. 2, 1920.

Application filed February 3, 1919. Serial No. 274,646.

To all whom it may concern:

Be it known that I, DAVID D. MORRIS, a citizen of the United States, residing at 354 Grant street, Paterson, in the county of 5 Passaic and State of New Jersey, have invented certain new and useful Improvements in Valve-Guards, of which the following is a specification.

My invention relates to improvements in 10 valve guards, and has particular reference to a casing adapted to be locked upon a valve, thereby inclosing the same and preventing the unauthorized operation thereof.

An important object of the invention is to 15 provide a device of the above-mentioned character, which is simple in construction, cheap to manufacture, and convenient in use.

Other objects and advantages of this invention will be apparent during the course 20 of the following description.

In the accompanying drawings forming a part of this specification, and in which like reference numerals are employed to designate like parts throughout the same:

25 Figure 1 is a plan view of a device embodying my invention;

Fig. 2 is a side elevation of the same;

Fig. 3 is a horizontal transverse sectional view through the device; and,

30 Fig. 4 is a central vertical longitudinal sectional view through the same.

In the drawings, wherein for the purpose of illustration is shown a preferred embodiment of my invention, the numeral 5 designates a valve, such as a shut-off valve in a 35 gas supply pipe.

My valve guard or casing embodies an upper portion or cap 6, which receives the upper reduced end 7 of the valve. The cap 6 is circular in horizontal cross section, as 40 shown in Fig. 1.

The body portion of the valve is preferably formed in two casing sections 8, which are semi-circular in horizontal cross section, 45 as clearly indicated in Fig. 3. These casing sections are hinged at their upper ends to the cap 6, as shown at 9, the hinges being preferably arranged at points equi-distantly spaced from the longitudinal edges of the 50 casing sections 8. The lower ends of the casing sections 8 are reduced and properly shaped to receive the lower end of the valve

and the valve stem 10. These lower ends carry extensions 11, having openings 12 receiving the shackle 13 of a pad-lock 14.

The casing sections 8 are provided at their edges with openings 15, receiving the pipe 16, to which the valve is connected. These openings extend through the upper ends of the casing sections, as shown.

From the foregoing description, it will be seen that the casing sections 8 may be swung to an open position and the cap 6 placed upon the top of the valve 5. Subsequently to this operation, the casing sections 8 are 65 swung to the inner or closed position, and held in such position by means of the pad-lock 14 or the like.

It is to be understood that the form of my invention herein shown and described is to 70 be taken as the preferred example of the same and that various changes in the shape, size and arrangement of the parts, may be resorted to without departing from the spirit of the invention or the scope of the 75 subjoined claim.

Having thus described my invention, what I claim is:

A guard for a valve connected in a pipe with portions of the pipe arranged upon opposite sides of the valve, comprising a cap adapted to be arranged upon the top of the valve and to snugly embrace said top, said cap being formed in one piece and comprising a body portion and a depending flange 80 carried thereby, casing sections arranged beneath the cap and adapted to surround and snugly embrace the body portion of the valve, said casing sections having portions thereof bent to engage beneath the lower end 85 of the valve to prevent upward displacement of the casing sections, and a portion of the guard inclosing the stem of the valve, means for pivotally connecting the upper ends of the casing sections with the cap, and means 90 to secure the lower ends of the casing sections together to prevent them from being moved apart.

In testimony whereof I affix my signature in presence of two witnesses.

DAVID D. MORRIS.
